The ornamental design for a panel display, as shown and described.

DESCRIPTION

FIG. 1 is a perspective view of a panel display showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view thereof; and,

FIG. 8 is an enlarged perspective view along the line 8-8 of FIG. 1.

Portions in broken lines are for illustrative purposes only and form no part of claimed design. Dot-dash broken lines define the boundaries of, but not included in, the claimed design.
